UNITED STATES PATENT OFFICE

2,147,827

AIR REGENERATOR FOR COKE OVENS

Maurice D. Curran, Glendale, Mo., assignor to
 Tar & Petroleum Process Company, Chicago,
 Ill., a corporation of Illinois

Application August 8, 1936, Serial No. 94,917

4 Claims. (Cl. 202—102)

The present invention relates to improvements in air regenerators for coke ovens.

More particularly the present invention relates to coke ovens of the Knowles type. An example of such an oven is disclosed in the patent to Knowles and McIntyre No. 1,635,280, granted July 12, 1927. A characteristic of this type of oven is that a layer of coal or other hydrocarbon containing material is heated from below, said layer of coal being shallow relative to its width. The coal or equivalent material is disposed on a horizontal floor heated by flues extending beneath said floor, the coking floor forming a part of the coking chamber, the oven having means for charging coal, means for withdrawing vapors and gases, means for sealing the ends of the chamber, and means permitting the pushing of the resulting coke out of the coking chamber.

It is common practice in connection with the ovens such as referred to to provide regenerative passageways placed below the heating flues to transfer heat to the incoming air. It has been found in practice that a very considerable amount of heat passes downwardly from the lowest of these regenerative passageways into the supporting pad therefor.

Subjects matter described but not claimed herein are claimed in copending applications Serial Nos. 94,916 and 94,918.

It is an object of the present invention to provide air passages in thermal communication with said concrete pad for utilizing the heat now lost through the foundations of a coke oven to preheat the air passing to the regenerative passages and thence to the heating flues of the coke oven.

It is common practice to arrange coke ovens in batteries, a number of ovens being placed side by side. According to certain aspects of the present invention, an object is to provide a construction having air passages disposed either longitudinally of a battery or transversely thereof (that is—longitudinally of the various ovens) for the purpose of utilizing the heat which has hitherto been lost through the foundations of the battery. A construction in which the air heating passages are disposed lengthwise of the battery presents the difficulty that the length of the battery is limited by reason of the practical limitation on the amount of air which can be drawn through along flues extending lengthwise of the battery. A further limitation of the construction just referred to is that it leaves something to be desired in the proper cooling of the foundations at the ends of the ovens where the downtakes

from the regenerative flues to the waste gas flues are located.

According to a preferred embodiment of the present invention, therefore, an object is to provide means for utilizing the heat heretofore lost in the foundations of coke ovens by a construction in which cooling air may be drawn transversely of the battery (that is—lengthwise of the individual ovens) through the foundations, whereby batteries of feasible length may be utilized without requiring excess draft through the air passages.

A further object is to provide an improved construction of coke oven in which cooling passages may be disposed in rather close proximity to the downtakes from the regenerative flues without danger of leakage.

A further object is to provide an improved coke oven construction in which heat units which hitherto have passed downwardly into the foundations and thence to the atmosphere may be utilized for preheating the air for combustion.

A further object is to provide a coke oven installation in which the work required of the fan for forcing air into the heating flues may be reduced.

A further object is to provide a coke oven installation in which air for the heating flues may be preheated with reduced friction losses.

Further objects will appear as the description proceeds.

Referring to the drawings—

Figure 1 is a vertical sectional view taken longitudinally of a battery of coke ovens, that is—transversely of the individual coke ovens, said view being taken along the plane indicated by the arrows 1—1 of Figure 2;

Figure 2 is a sectional view taken along the plane indicated by the arrows 2—2 of Figure 1; and

Figure 3 is a horizontal sectional view taken along the plane indicated by the arrows 3—3 of Figure 1.

Referring to Figure 1, the numerals 10—10 indicate a plurality of coke ovens arranged side by side to form a battery. Each of said ovens comprises a coking chamber 11 having a horizontal floor 12 and a roof 13. Common pier walls 14—14 separate adjacent ovens and provide supports for the adjacent roofs 13—13. The coking chambers are commonly of a height relatively small compared to their width and length. Each of said chambers will be provided with end doors 15 and 16 through which the resulting coke may be pushed out of the coking chambers. Each 55

of said chambers will also be provided with means (not shown) for charging coal, and means for withdrawing vapors and gases.

According to usual practice in the Knowles type 5 of oven, a plurality of heating flues 17-17 are disposed below the floor 12 of each oven in thermal communication with said floors. Said flues are defined by the horizontal wall 18 and the vertical walls 19-19. Said horizontal wall 18 10 provides openings 20-20 from the heating flues 17 to the space below said flues, said openings 20-20 being located adjacent to the end walls of each of the ovens. Disposed medially of each of the ovens is the vertical wall 21 extending transversely 15 of each of said ovens. Each of said medial walls 21 extends downwardly from the horizontal wall 18 to the foundations of the corresponding oven and divides the space below the wall 18 of each oven into two regenerative chambers. Extending 20 from each end wall of each oven is the horizontal partition wall 22 disposed below and in spaced relationship with the wall 18. Each of said walls 22-22 at the region adjacent to the medial wall 21 has an aperture 23 providing communication 25 between the region above and the region below the corresponding wall 22. Expressed in other language, the horizontal wall 22 at each end of each oven provides a U-shaped passageway or hairpin passageway from the region at the bottom of the oven adjacent to the end wall thereof to the medial region of the oven and back adjacent to the end wall, where communication is had through the apertures 20 to the heating flues 17. According to usual practice, waste gas tunnels 30 24-24 are provided at the ends of the ovens, that is—extending longitudinally of the battery of ovens along the pusher side and the coke side of a battery of ovens. Downtakes 25-25 provide communication from the regenerative chambers at each end of each oven with said waste gas tunnels.

According to usual practice, the coke ovens are supported by pads 26 of concrete or the like. According to a preferred embodiment of the present invention and as illustrated in the drawings, 45 air passageways are provided through or adjacent to said pads 26, which passageways are disposed lengthwise of the various ovens, that is—transversely of a battery of ovens. The numeral 27 indicates such air passageways. It will be noted 50 that said air passageways 27 extend from the ends of the ovens to downtakes 28-28 adjacent to the medial wall 21, and lead to the air suction flue 29. Said air suction flue is preferably connected to a fan box 30, which through air passages 31-31 connects with the air manifolds 32-32 55 extending longitudinally of the battery of ovens at the two ends of the individual ovens. Said air passages 31-31 may be controlled by 60 valves 31a-31a. Said air manifolds 32-32 are provided with air inlets 33 communicating with the regenerating chambers at the two ends of the ovens. The numerals 34-34 indicate gas manifolds, which through gas inlets 35-35 65 connect with the heating flues 17-17 at the two ends of the ovens.

A problem which has confronted applicant in providing the construction above described has been to prevent communication between the gas 70 downtakes 25-25 and the air passages 27-27. Inasmuch as said air passages 27-27 pass in close proximity to the gas passages 25-25, leakage is likely to occur therebetween unless effective means are provided for preventing such leakage. 75 According to the present invention, the pad 26 has

thereon a plurality of blocks 36-36. Said blocks 36-36 are preferably rectangular in outline and are provided with the central apertures 37-37. Said blocks 36-36 are mounted upon the pad 26 with their apertures 37-37 in registry with the 5 downtakes 25-25. Said blocks 36-36 are spaced apart, as indicated by the numerals 38-38, to provide passageways aligned and in communication with the passageways 27-27 formed in the brickwork of the ovens. It will be noted from an 10 inspection of Figure 1 that said blocks 36-36 are mounted in their spaced relationship continuously from oven to oven. The air passages 27-27 in alignment with the spacing between said blocks 36-36 also are disposed in spaced relationship 15 from oven to oven, whereby the cooling effect of said passageways 27-27 is had through the pier walls 14-14. The blocks 36-36 may be of clay, brick or tile, or other preferred construction having the necessary ruggedness and resistance to 20 temperature conditions.

Though a preferred embodiment of the present invention has been described in detail, many modifications will occur to those skilled in the art. It is intended to cover all such modifications 25 that fall within the scope of the appended claims.

What is claimed is—

1. In a coke oven or the like, in combination, a floor, heating flues disposed below said floor extending throughout the length thereof, a pair 30 of regenerative chambers below said heating flues, means dividing said chambers medially of the length of said oven, one of said chambers having communication with said flues at one end of said flues, the other of said regenerative chambers 35 having communication with said flues at the other end of said flues, means for admitting gas to the two ends of said flues, foundation means providing downtakes from said regenerative chambers, said foundation means being provided 40 with air ducts extending therealong, and means for circulating air through said air ducts to one of said regenerative chambers and for withdrawing products of combustion from said flues through the other of said regenerative chambers, 45 said downtakes being positioned to extend downwardly between said air ducts, said regenerative chambers having connections thereto whereby flow through said regenerative chambers may be reversed.

2. In a coke oven or the like, in combination, a floor, heating flues disposed below said floor extending throughout the length thereof, a pair of regenerative chambers below said heating flues, means dividing said chambers medially of the 55 length of said oven, one of said chambers having communication with said flues at one end of said flues, the other of said regenerative chambers having communication with said flues at the other end of said flues, means for admitting gas to the two ends of said flues, foundation means providing 60 downtakes from said regenerative chambers, said foundation means being provided with air ducts extending therealong, and means for circulating air through said air ducts to one of said regenerative chambers and for withdrawing products of combustion from said flues through the other of said regenerative chambers, said 65 downtakes being positioned to extend downwardly between said air ducts, said circulating and withdrawing means including tunnels located adjacent to the ends of said flues, and a tunnel communicating with said air ducts at a region disposed medially of the length of said oven, said regenerative chambers having connections thereto 70 75

whereby flow through said regenerative chambers may be reversed.

3. In a coke oven or the like, in combination, a floor, heating flues disposed below said floor 5 extending throughout the length thereof, a pair of regenerative chambers below said heating flues, means dividing said chambers medially of the length of said oven, one of said chambers having communication with said flues at one end of said flues, the other of said regenerative chambers having communication with said flues at one end of said 10 flues, the other of said regenerative chambers having communication with said flues at the other end of said flues, means for admitting gas to the two ends of said flues, foundation means providing downtakes from said regenerative chambers, said foundation means being provided with air ducts extending therealong, and means for circulating air through said air ducts to one of said regenerative chambers and for withdrawing products of combustion from said flues through 15 the other of said regenerative chambers, said 20 downtakes being positioned to extend downwardly between said air ducts, said downtakes being defined in part by preforming apertured blocks, said blocks being spaced apart to define portions of said air ducts, said regenerative chambers having connections thereto whereby flow through 25 said regenerative chambers may be reversed.
4. In a coke oven or the like, in combination, a floor, heating flues disposed below said floor

extending throughout the length thereof, a pair of regenerative chambers below said heating flues, means dividing said chambers medially of the length of said oven, one of said chambers having communication with said flues at one end of said flues, the other of said regenerative chambers having communication with said flues at the other end of said flues, means for admitting gas to the two ends of said flues, foundation means providing downtakes from said regenerative chambers, said foundation means being provided with air ducts extending therealong, and means for circulating air through said air ducts to one of said regenerative chambers and for withdrawing products of combustion from said flues through 10 the other of said regenerative chambers, said 15 downtakes being positioned to extend downwardly between said air ducts, said circulating and withdrawing means including tunnels located adjacent to the ends of said flues, and a tunnel communicating with said air ducts at a region disposed medially of the length of said oven structure, said 20 downtakes being defined in part by preformed apertured blocks, said blocks being spaced apart to define portions of said air ducts, said 25 regenerative chambers having connections thereto whereby flow through said regenerative chambers may be reversed.

whereby flow through said regenerative chambers may be reversed.

3. In a coke oven or the like, in combination, a floor, heating flues disposed below said floor 5 extending throughout the length thereof, a pair of regenerative chambers below said heating flues, means dividing said chambers medially of the length of said oven, one of said chambers having communication with said flues at one end of said flues, the other of said regenerative chambers having communication with said flues at one end of said 10 flues, the other of said regenerative chambers having communication with said flues at the other end of said flues, means for admitting gas to the two ends of said flues, foundation means providing downtakes from said regenerative chambers, said foundation means being provided with air ducts extending therealong, and means for circulating air through said air ducts to one of said regenerative chambers and for withdrawing products of combustion from said flues through 15 the other of said regenerative chambers, said 20 downtakes being positioned to extend downwardly between said air ducts, said downtakes being defined in part by preforming apertured blocks, said blocks being spaced apart to define portions of said air ducts, said regenerative chambers having connections thereto whereby flow through 25 said regenerative chambers may be reversed.
4. In a coke oven or the like, in combination, a floor, heating flues disposed below said floor

extending throughout the length thereof, a pair of regenerative chambers below said heating flues, means dividing said chambers medially of the length of said oven, one of said chambers having communication with said flues at one end of said flues, the other of said regenerative chambers having communication with said flues at the other end of said flues, means for admitting gas to the two ends of said flues, foundation means providing downtakes from said regenerative chambers, said foundation means being provided with air ducts extending therealong, and means for circulating air through said air ducts to one of said regenerative chambers and for withdrawing products of combustion from said flues through 10 the other of said regenerative chambers, said 15 downtakes being positioned to extend downwardly between said air ducts, said circulating and withdrawing means including tunnels located adjacent to the ends of said flues, and a tunnel communicating with said air ducts at a region disposed medially of the length of said oven structure, said 20 downtakes being defined in part by preformed apertured blocks, said blocks being spaced apart to define portions of said air ducts, said 25 regenerative chambers having connections thereto whereby flow through said regenerative chambers may be reversed.
